UNITED STATES PATENT OFFICE.

ATTILIO REGULUS SPICACCI, OF WEST HOBOKEN, NEW JERSEY.

TONE-ARM BASE.

1,363,061.

Specification of Letters Patent. Patented Dec. 21, 1920.

Application filed January 14, 1920. Serial No. 351,274.

To all whom it may concern:

Be it known that I, ATTILIO REGULUS SPICACCI, a citizen of Brazil, and a resident of West Hoboken, in the county of Hudson and State of New Jersey, have invented a new and useful Tone-Arm Base, of which the following is a full, clear, and exact description.

This invention relates to talking machines, and particularly to an improved tone arm and base which is simple and comparatively cheap to manufacture, while at the same time presenting a structure capable of causing a proper discharge of the sound.

Another object of the invention is to provide a base and tone arm constructed to permit a free turning movement, while at the same time presenting a mechanical construction which will not readily get out of order and which will wear for a long time.

In the accompanying drawing:

Figure 1 is a longitudinal vertical section through part of a talking machine, the same disclosing an embodiment of the invention.

Fig. 2 is a fragmentary sectional view through Fig. 1 on line 2—2.

Fig. 3 is a front view of the base shown in Fig. 1, the same illustrating certain parts of the invention.

Referring to the accompanying drawing by numerals, 1 indicates a casing of a talking machine provided with a base board or section 2 and a cover 3 hinged in any suitable manner so as to readily open and close.

The base board 2 is provided with an opening 4, but registers with the lower part of the base 5. Base 5 is preferably made from metal and is preferably round in cross section, the same being formed with a flange

6 through which the retaining grooves 7 project. The upper part of the base preferably slightly tapers, and is offset at 8 so as to receive the cap 9 in the offset portion and gives substantially the appearance of a continuous moving base member to the top of the tone arm 10. This tone arm is preferably formed integral with the cap 9 and continually registers with the opening 11 in the base 5, whereby the sound may properly

pass through the base regardless of the position of the tone arm. A filler block 12 is

provided in the upper part of the base 5, said block being formed integral with the base 5, or rigidly secured in place in any desired manner. Block 12 is formed with an inclined face 13 set in such a position as to face the opening 11 whereby it acts as a deflector for the sound waves. In addition to acting as a deflector the block 12 acts as a support for the tone arm, the action being through a bearing pin 14 rigidly secured in any desired manner to the top of cap 9. As shown in Fig. 1, the top of cap 9 is provided with an enlargement 15, in which the upper end of pin 14 is fitted, the same being preferably cast in place. The lower end of the pin 14 is pointed and fits at the lower end in socket 16 in the block 12, said socket having a tapering bottom whereby there is a pointed support for the cap 9 and tone arm 10. It will be noted that the cap 9 is slightly larger than the upper part of the base 5, whereby the tone arm 10 may move upwardly and downwardly freely within certain limits and thereby answer the usual requirements while the arm is permitted a free action in its back and forth movement, as it passes over a record.

What I claim is:

1. A tone arm and base comprising a base member, a tone arm provided with a cap loosely fitting over the base member, said base member having an opening so that the sound may freely pass from the tone arm into the base member, and a pivotal pin engaging the cap and the upper part of the base member acting as a support for the cap and tone arm, said pin being provided with a substantially pointed end for permitting a free swinging movement of the tone arm. 80

2. A combined tone arm and base comprising a tone arm provided with a cap having an opening in the side, a hollow base provided with an opening in one side adapted to register with the opening in said cap, 95 said base being formed with a contracted upper part over which the cap loosely fits, said base having a socket in the upper part and a supporting pin connected with the cap engaging the base at the bottom of said socket. 100

3. A combined tone arm and base com-

prising a tone arm provided with a cap, a base having a restricted upper part loosely fitting within the cap, a filler block arranged within said base formed with a
5 socket in the upper part and an inclined lower face positioned to face the tone arm, and means projecting from the cap and en-
gaging the bottom of said socket for supporting said cap so as to permit a free swinging movement of the cap and tone arm.

ATTILIO REGULUS SPICACCI.
